CLOTHES WRINGER

Walter A. Frantz, Cleveland Heights, and John J. McCabe, Cleveland, Ohio, assignors to The Apex Electrical Manufacturing Company, Cleveland, Ohio, a corporation of Ohio

Application August 8, 1933, Serial No. 684,204

17 Claims. (Cl. 68—32)

This invention relates to clothes wringers of the type disclosed in our copending application for U. S. Letters Patent Serial No. 613,999, filed May 27, 1932 for Clothes washers and the present application constitutes a continuation in part of our above referred to copending application.

This invention has for its objects the provision of an improved clothes wringer operating mechanism, improved and easily operated controls for 10 such mechanism and improved safety devices for preventing the connection of the wringer rolls to the power drive when the wringer swing-lock is released and for quickly and easily releasing the pressure between the wringer rolls which 15 means also operate to disconnect the driving connection of such rolls with a source of power.

With these and other objects in view, the invention consists in the novel construction, arrangement and combination of parts, hereinafter 20 illustrated and described in some of its embodiments in the accompanying drawings, and particularly pointed out in the appended claims.

In the drawings, Figure 1 is a sectional side 25 elevational view of a clothes wringer taken through the axis of the wringer rolls and the wringer driving shaft illustrating one mode of practicing the invention.

Figure 2 is a sectional view taken on line 2—2, Figure 1.

Figure 3 is an enlarged view of certain details 30 of the wringer clutch mechanism used in connection with the wringer shown in Figure 1.

Figure 4 is a sectional view taken on line 4—4, Figure 1.

Figure 5 is an enlarged sectional view taken on line 5—5, Figure 1.

Figure 6 is an enlarged detail sectional view taken on line 6—6, Figure 1.

Figure 7 is an enlarged detail sectional view 40 taken on line 7—7, Figure 1.

Figure 8 is an enlarged detail sectional view taken on line 8—8, Figure 1.

Figure 9 is a plan view of another form of wringer gearing illustrating another mode of utilizing some of the features of this invention.

Figure 10 is an enlarged sectional view taken on line 10—10, Figure 9.

Figure 11 is a sectional view taken on line 11—11, Figure 9.

Figure 12 is a side elevational view of yet another form of wringer driving mechanism which includes the general features of construction of the gearing shown in Figures 9 to 11, differing 55 principally therefrom in that the wringer drive

control and swing-lock are operatively associated with each other.

Figure 13 is a sectional view taken on line 13—13, Figure 12; and

Figure 14 is a sectional view taken on line 5—5, Figure 12.

In the form of the invention illustrated in Figures 1 to 8 inclusive, the numeral 1 indicates a vertical wringer supporting column which may as is customary, terminate at a level at or above 10 the top of the tub (not shown) of the washing machine with which the wringer is associated. The column 1 is provided with a flanged collar 2 having circumferentially spaced notches 3 for the reception of the lower end of the lever 4 of 15 a locking device, by means of which the wringer may be held in the various adjusted positions about the axis of its supporting column 1.

In the present case the wringer is used in connection with a washing machine of the type having an insulating shield 5 radially spaced from the washer tub. A top plate 6 is fitted over the top of the shield and the washing machine tub and this shield may extend inwardly beyond the edge of the tub to provide both a working 20 aperture above the tub and a seat for the customary tub cover. This form of casing construction is well understood and is not illustrated in detail in this application. The top plate is formed with an opening between the tub 25 side wall and the shield defined by the downwardly turned annular flange 7 in which the collar of the wringer supporting column is fitted.

The wringer gearing is housed within a casing 8 and it comprises a gear case 10, the lower 30 part of which is provided with an annular flange 11 which rests on the shoulder 2 of the wringer supporting column. The casing 8 is secured to the flange 11 by any suitable means such as screws 8a, one of which is shown in Figure 1. A 35 boss 12 is provided on the side of the gear case at a point above the flange 11 for a pin 13 by means of which the swing-lock lever 4 is pivotally secured to the wringer gear case.

The swing-lock lever has an arm 14 extending 40 above the pivotal bearing provided by the pin 13. The arm 14 is urged away from the gear case and the swing-lock is urged to locking position by means of a coil spring 15. The arm 14 is provided with an upwardly extending annular part which surrounds the upper part of the gear case 10 and at its upper extremity it is provided with a cam shaped part 16 the purpose of 45 which will be described in detail presently.

The wringer swing lock is released to permit 50 55

movement of the wringer about the axis of its supporting column by manually pressing the upper part of a movable section 17 of the casing or housing 8. The lower end of this section of the housing is pivoted at 18 to the body of the housing 8 and the upper end is in contact with the arm 14 so that by pressing the section 17 inwardly the arm 4 is moved out of registry with one of the notches 3 and the wringer can then be swung to the desired position whereupon the section 17 is released and the spring 15 forces the lower end of the lever 4 into one of the notches 3 of the collar of the wringer supporting column.

15 The wringer gear case 10 is formed at its upper end with a horizontal hollow cylinder having reduced circular end parts and which is formed by the upper and lower halves 20 and 21, the latter of which is integral with the rest of the gear case. The reduced ends provide bearings for the enlarged parts 22 and 23 of the horizontal wringer driving shaft 24. The parts 22 and 23 are pinned or otherwise fixedly secured to the shaft 24. A pair of beveled gears 25 and 26 are rotatably journaled on the shaft 24. A spacer ring 27 is loosely interposed between the gears to keep them properly spaced from each other. The beveled gears 25 and 26 mesh at all times with a beveled pinion 28 which is fixedly secured on to the upper end of a vertical wringer driving shaft 29.

The vertical driving shaft 29 is journaled at its upper end in a sleeve 30 rigidly carried by the gear case 10. The sleeve has a bearing surface for contact with the shaft at its upper end. The lower part of the sleeve extends a considerable distance beyond the lowermost part of the wringer gear case 10 and it has a plurality of stiffening ribs and rings 31 formed externally thereof for contact engagement with the gear case 10 and with the wringer supporting column 1 and it is by means of this sleeve that the wringer is removably and rotatably carried in the end of the wringer supporting column 1.

45 During the operation of the vertical drive shaft 29, the beveled gears 25 and 26 are continuously rotated in opposite directions by the beveled pinion 28. Clutches are provided for selectively connecting one or the other of the beveled gears 50 25 or 26 in driving relation to the horizontal wringer drive shaft 24. These clutches comprise a pair of coil springs 32 and 33 which may be formed from a length of spring steel wire of square or rectangular cross section. One end 34 55 of the spring 32 engages an outer cylindrical clutch control member 35 and the opposite end 36 of this spring engages a cylindrical clutch member 37 which is rotatably fitted in the member 35.

60 The clutch member 35 is provided with an annular toothed flange 38 and the member 36 is also provided with an annular toothed flange 40 located alongside of the flange 38. The clutch spring 33 is connected in a similar manner to a 65 pair of cylindrical clutch control members 42 and 43 which are substantial duplicates of the members 35 and 37 respectively.

A segment 44 pivoted on a pin 45 and having an operating bar 46 fixed to its upper edge is provided for controlling the operation of the clutches. A ball and spring detent 47 cooperates with three notches 48 provided in the housing 8 to maintain the clutch control segment 44 in any one of its three operating positions.

75 When the segment 44 is in the position shown

in Figure 1 its lowermost notched end parts 50 and 52 are in engagement with the toothed flanges of the clutch members 35 and 37 and 42 and 43, thereby holding these members and their associated springs in a fixed immovable position. 5 The teeth of the flanged portions of the aforesaid clutch members are normally held by the clutch springs with their teeth out of alignment by a distance approximately equal to one-half a tooth so that when the segment engages the 10 toothed portions of the clutch members these clutch members are rotated in opposite directions to bring the teeth of the flanged portions thereof into substantial alignment.

This action loosens or unwinds the springs 32 15 and 33 thereby releasing the beveled gears 25 and 26 and enlarged horizontal driving shaft parts 22 and 23 from frictional driving engagement with the springs 32 and 33. When the left hand side of the control member 46 is depressed the 20 notched part 52 of the segment 44 moves completely out of registry with the notched parts of the clutch members 42 and 43. This permits the tensioned clutch spring 33 to wind up on the beveled gear 26 and the shaft part 23 whereupon 25 these parts are frictionally connected to each other and the lower roll is driven by the pinion 28 and the beveled gear 26.

Similarly when the right end side of the control member 46 is depressed the notched part 50 30 of the segment moves out of registry with the toothed portions 38 and 40 of the associated clutch members 35 and 37 whereupon the spring 32 grips the beveled gear 25 and the enlarged shaft part 22 connecting these two parts in driving engagement with each other. In either case the relative angular position of the cylindrical clutch members is not disturbed during the actuation of the corresponding, oppositely located clutch members.

40 The driving engagement last referred to drives the horizontal shaft 24 in a reverse direction. The aforesaid clutching device provides an arrangement which operates instantly with the slightest pressure on the part of the operator 45 thereby providing a sensitive finger operated wringer control. To place the control in neutral position all that is necessary is merely to rest the palm of the hand upon the control lever 45 which instantly brings all of the clutch parts to 50 their disengaged position.

The wringer gearing control just described for convenience may be characterized as a "fingertip" control. This expression is intended to include wringer controls which may be operated by the exertion of as little pressure as that which the ordinary users of a wringer are capable of exerting with one or more of their fingers. The ease with which this control may be manipulated results principally by reason of the utilization of 60 part of the energy of the power driving means of the wringer in effecting the power driving connection for rotating the wringer rolls in one direction or the other. The stopping of the wringer rolls is accomplished simply by moving a detent 65 in the path of the drive connecting device. The power drive connection just referred to is commonly called the "servo-type" which expression is also often used in connection with brakes and other devices in which the operator initiates a 70 step or series of steps in the operation of a device which step or steps are completed by some agency other than the operator.

The wringer rolls 86 and 87 are carried in a supporting frame 53 having upper and lower sets 75

of bearings 54 and 55 for the shafts 56 and 57 of the upper and lower wringer rolls. The shaft 57 of the lower wringer has a detachable universal driving connection 58 with the horizontal wringer driving shaft 24. A flat spring 60 engages the upper wringer roll bearings 54 to urge the wringer rolls into resilient engagement with each other.

A screw 61 having an operating handle 62 is threaded in a detachable channeled cross bar 63 of the wringer frame to effect the adjustment of the flat roll tensioning spring 60. The cross bar 63 is normally locked to the wringer frame by means of a pair of latch members 64 and 65 which are secured for movement in the bar by 15 the pins 66 and 67. The latch members are provided with extensions 68 and 70 which engage with the cut-out portions 72 and 73 of the stiles of the wringer frame 53, and thus serve to hold the cross bar in locked position.

20 The inner ends of the latch members 64 and 65 are formed with tongues 74 and 75 which are normally held in latch locking position by means of a pivotally movable plate member 76 having contacting end parts 77 and 78 which engage 25 the parts 74 and 75 respectively of the latch members. The plate member 76 is connected to a pair of cross members 80 and 81 which at their outer ends normally carry a pair of safety release bars in the position shown in Figure 5. 30 A slight pressure exerted towards the wringer on either one of the safety bars 82 or 83 quickly releases the latches 74 whereupon the tension between the wringer rolls 86 and 87 is instantly released. Members 79 riveted to the bar 63 have 35 apertures for receiving the ends 77 of the plate 76 to limit the movement of the same.

The upper portion of the member 76 is pivoted at 88 and 90 to the cross bar 63. One end of the upper part of the member 76 is engaged by 40 ears 91 formed on a member 92 which is rigidly attached to the inner end of a rod 93. The other end of the rod is journaled in the bar 63 and has fixed to it at this point a forked crank 94 which engages the upper end of a lever 95, having a pivotal support 96 at a point intermediate 45 its ends. The lower end of the lever 95 has a cam-shaped aperture 97 within which is received an arm 98 extending from and rigid with the segmental control member 44.

50 When the aforesaid safety release is operated, the actuation of the parts 76, 93 and 95 and the interaction between the cam 97 and the arm 98 serve to shift the wringer clutch control to neutral position by either raising or lowering the 55 arm 98 to its intermediate position depending upon the direction of the rotation of the wringer rolls. The safety control just described not only serves to release the tension between the wringer rolls 86 and 87 but it also operates to stop any 60 further movement of the wringer rolls.

As an added safety feature the swing-lock and wringer clutch control cooperate with each other to prevent the operation of the wringer rolls except at such times as when the control device 65 is in neutral position and the wringer rolls are not moving. This highly desirable result is accomplished by means of the cooperation between the cam member 16 of the swing-lock lever and a notch 100 of the control segment 44.

70 When the control segment 44 is in neutral position the notch 100 is located so as to readily and freely receive the cam part 16 of the swing-lock lever and it is therefore possible with the parts in such position to shift the arm 4 of the swing lock out of registry with the notches 3. When

the control segment 44 is shifted to either of its operating positions the notch 100 is moved to an upper or a lower position where it cannot accommodate the cam member 16 and under such conditions it will be impossible to shift the arm 4 out of engagement with any of the notches 3 with the control segment in driving position by reason of the fact that the adjacent edge of the segment 44 will not permit sufficient movement of the arm 4 to effect the release of the 10 swing-lock without first causing the control segment to move to its neutral position. When the cam 16 is located in the aperture 100 operation of the wringer control segment 44 is prevented and it is impossible to place the wringer in 15 operation with the swing-lock lever in such position. Due to the shape of the cam 16 and the contour of the sides of the notch 100, movement of the segment 44 tends to shift the swing-lock lever to its locking position and movement of 20 the lever from such position tends to restore the segment to its neutral position if it is not already in such position.

The bottom part of the wringer is provided with a pan 101 which catches part of the water 25 which is squeezed from the clothes during the operation of the wringer. This pan is depressed at its center where it has an aperture 102 which communicates with a drain member 103 by means of which such water is returned to the 30 tub or container on the feeding side of the wringer or on the side of the wringer at which clothes are being fed.

The form of wringer gearing illustrated in Figures 9, 10, and 11 corresponds exactly to the 35 form of wringer gearing mechanism illustrated in the referred to copending application for U. S. Letters Patent of which the present case forms a continuation in part. This form of wringer mechanism is an improvement of the mechanism 40 disclosed in Patent Number 1,830,406, issued to J. L. Perkins et al. November 3, 1931, and differs therefrom in several important details as will be pointed out presently.

In this latter form of construction, the wringer 45 is driven by a vertical drive shaft 104 which is journaled in a bearing member 105, fixedly secured in the wringer gear case housing 106 by means of a bolt 107. This bolt extends in both directions beyond its head or wrench engaging 50 portion. The unthreaded extension 108 of the bolt is provided for carrying a spring 110 by means of which the swing-lock lever 111 is held in locked position. This lever is pivoted at 112 to the wringer gear case 106 and it has a part 55 113 extending below its pivot which is provided for locking engagement with any one of the notches 114 of an annular collar 115 carried by a wringer column 116.

The bearing member 105 extends for some distance beyond the housing 106 and it is of such size as to be removably fitted into the wringer supporting column 116 to hold the wringer for movement about the column axis. The flanged end 117 of the wringer housing rests upon the 60 collar 115 which is carried at the top of the wringer supporting column.

The wringer gear housing 106 is formed from a single die casting and the mechanism inclosed therein is arranged and constructed so that the 65 operating elements of the wringer may be assembled and installed in this case by way of the necessary shaft openings, through which the driving and the driven shafts of the mechanism extend. This construction eliminates the use of 70 75

either a cover plate or a sectional gear case, as are customary forms of construction for this element of a washing machine.

The inside diameter of the major portion of the bearing member 105 is of slightly larger diameter than the shaft 104. The upper end portion of the bore of the bearing member 105 is of such size as to provide a suitable bearing 118 for the upper end of the shaft 104. The purpose of this bearing arrangement is to prevent binding of the shaft 104 in its bearing. The shaft 104 is threaded at 120 to receive the threaded beveled pinion 121. The beveled pinion is positioned between a pair of similarly formed beveled gears 122 and 123 respectively.

The beveled gears 122 and 123 are secured to each other by means of a sleeve 124 to which the gears are welded. The gears, in turn, are mounted upon a hollow shaft 125 and are secured thereto by means of a pin 126. A bearing 127, is provided in one end of the gear case for the rotatable reception of the hollow shaft 125. The other end of the shaft 125 is journaled in the rotatable bearing block 128.

The bearing block 128 is rotatably supported or journaled in the casing 106 and is axially movable to various adjusted positions by means of a handle 130, which is received in the threaded hole 131 of the bearing block. The handle 130 is utilized to secure a cover plate 132 over the cam slot 134. The portion of the cover plate receiving the handle 130 is fitted with a rotatable annular sleeve or bushing 135, which engages the sides of the cam slot 136 formed in the top part 35 of the casing 106 and acts as a roller bearing to prevent undue wear on either the cam slot or the part provided to engage the slot.

The lower portion of the bearing member 128 is provided with a blind hole for receiving in the order named, a spring 137 and a ball 138. The lower portion of the interior face of that part of the housing 106 which is adjacent to the wringer, is provided with three slots 140, 141 and 142. These slots receive at different times, the spring pressed ball 138 and serve to maintain the operating lever 130 and the beveled gears 122 and 123 in neutral, forward or reverse driving positions respectively.

As viewed in Figure 11, when the handle 130 is pushed away from the operator, the gear 123 is brought into mesh with the pinion 121 and the wringer is driven in a direction to carry clothes away from the operator who is presumably in front of the wringer. With the parts in this 55 position, the ball 138 is in the slot 140 and serves to maintain the gears in mesh. When the handle is in a vertical position the gears are in neutral position and the ball engages with the slot 141. The wringer is driven in a reverse direction by 60 moving the handle toward the operator as viewed in Figure 11, whereupon the gear 122 is brought into mesh with the pinion 121 and the ball 138 engages with the slot 142 to hold the gears in mesh.

The movement of the beveled gears is transmitted to the wringer rolls by means of a coupling 143, which is slotted at 144 for receiving the pin 145 and its rotatable bearing sleeve 146. The pin 145 is fixedly secured in the hollow shaft 125 70 and is rotatable therewith. The shaft 147 of the lower wringer roll 148 is flattened at its end for reception in a similarly formed opening provided by the coupling member 143. The coupling member is secured to the roll shaft by means of a 75 cotter pin 149.

An interiorly threaded cup 150 is welded or otherwise secured to the side member or stile 151 of the wringer frame. The cup 150 is received on the exteriorly threaded end of the wringer gear case 106. A set screw 152 is provided to lock the cup 150 in its proper position. This arrangement illustrates a simple and inexpensive way of detachably securing the wringer to the wringer gear case. 5

The angle between the axes of the vertical and horizontal portions of the gear case 106 is slightly in excess of 90° so that the sagging due to the weight of the wringer and the necessary clearances between the bearing member 104 and the tube 116 and case 106 are compensated for, and when assembled, the wringer assumes a substantially horizontal position. 10

In the form of the device illustrated in Figures 12, 13, and 14, additional means are provided for insuring that the wringer control is always 20 in neutral position when the wringer is swung about its vertical axis. This mechanism comprises a rod 153 which is pivotally connected at 154 to the swing-lock lever 111. The other end of this rod is provided with a curved end part 25 155 which is arranged to contact at times with one arm of a lever 156, pivoted at 157 in the gear case 158. The curved end part of the rod is also arranged to engage with the roller 160 of the control lever 161. The roller 160 moves in 30 a cam slot 162 of similar design to the slot 134.

With the lever 161 in either one of its wringer roll driving positions when the end 113 of the swing lock lever 111 is moved out of disengagement with one of its notches 114 the lever 161 is 35 automatically shifted to the full line or neutral position as shown in Figure 14. This result is accomplished by the curved end part 155 of the rod 153 engaging directly with the control lever roller 160 to shift it to its neutral position or by 40 the actuation of the rod of the lever 156 which serves to return the control lever to neutral when it is in its other position of operation. By reason of this arrangement it is impossible to swing the wringer without first disconnecting the 45 wringer rollers from driving engagement with the vertical driving shaft of the wringer.

The control members 46 and 161 function substantially the same in both forms of the invention in-so-far as their interaction with the swing-lock is concerned. When the swing-lock lever is in its disengaged position the stated control members are held in their neutral position. In each case the unlocking movement of the swing-lock lever will return the corresponding gear control member to its neutral position if it is not already in such position and movement of the gear control member from neutral position will tend to move the corresponding swing-lock member into locking position if it is not already 60 in such position.

Furthermore, it is to be understood that the particular forms of apparatus shown and described, and the particular procedure set forth, are presented for purposes of explanation and 65 that various modifications of said apparatus and procedure can be made without departing from our invention as described in the appended claims.

Having thus described our invention what we 70 claim is:

1. In a wringer mechanism, a wringer gear case having horizontal and vertical portions, a wringer supported on the horizontal portion of said gear case, a removable bearing member received in 75

the vertical portion of said gear case and projecting therefrom, a hollow wringer column for receiving the projecting end of said bearing member, a control lever pivoted to said gear case, a boss formed on said lever, a bolt having an elongated head for holding said bearing in place, and a compression spring carried by and encircling said boss and bolt head.

2. In a wringer mechanism, a wringer gear case having horizontal and vertical portions, a wringer supported on the horizontal portion of said gear case, a removable bearing member received in the vertical portion of said gear case and projecting therefrom, a hollow wringer column for receiving the projecting end of said bearing member, a control lever pivoted to said gear case, a bolt having an elongated head for holding said bearing in place, and a compression spring carried by said bolt and engaging said lever.

3. In a wringer mechanism, a wringer gear case having horizontal and vertical portions, a wringer supported on the horizontal portion of said gear case, a support member secured in the vertical portion of said gear case and projecting therefrom, a hollow wringer column for internally and rotatably receiving the projecting end of said support member and providing a bearing therefor, and means for holding said support member in place in said gear case.

4. In a laundry machine, a gear case having openings for the reception of a vertical driving shaft and a horizontal driven shaft; a wringer having a roll adapted to be operatively connected to said driven shaft, means including said gear case for detachably supporting the wringer on the machine for movement about a vertical axis, and reversing gearing interposed between said shafts and housed in said case, said shafts being fitted in said gear case with their axes forming an angle of slightly more than ninety degrees.

5. A wringer drive for washing machines comprising, a one-piece gear case having openings for the reception of a control handle, a driving shaft and a driven shaft; said case being otherwise closed and free from openings, reversing gearing housed in said case and insertable through the stated shaft openings, the opening for said handle being in the form of an elongated slot, and a cover for said slot held in place by said control handle.

6. In a control device for swinging wringers, the combination with a wringer-drive gearing and a swing-lock, of means including interacting, individual, selectively operable, manual control members for said gearing and swing-lock, the actuation of the control member of said swing-lock operating to shift said gear control member from its gear driving position.

7. In a control device for swinging wringers, the combination with a wringer-drive gearing and a swing-lock, of individual, selectively operable, manual control members for said gearing and swing-lock, and means associated with said swing-lock control member adapted upon its actuation to return said gearing control member to a predetermined position.

8. In a control device for swinging wringers, the combination with a wringer-drive gearing and a swing-lock, of individual, selectively operable, manual control members for said gearing and swing-lock, and interacting means between said swing-lock control member and said gearing control member for preventing the actuation of said gearing control member except when said

swing-lock control member is in its locked position.

9. In a wringer mechanism, a wringer gear case having upper and lower portions, a wringer supported from the upper portion of said gear case, a support member secured in said gear case and projecting from the lower portion thereof, a shaft rotatably journaled in said support member and having a gear at its upper end, said support member, shaft and gear being insertable as a unit in said gear case, a hollow wringer column for internally and rotatably receiving the projecting end of said support member and providing a bearing therefor, and means for holding said support member in place in said gear case.

10. In a wringer mechanism, a wringer gear case having upper and lower portions, a wringer supported from the upper portion of said gear case and projecting in a horizontal direction outwardly therefrom, a support member secured in said gear case and projecting from the lower portion thereof, a hollow wringer column for internally and rotatably receiving the projecting end of said support member and providing a bearing therefor, said support member forming an angle slightly in excess of ninety degrees with the wringer so as to compensate for the sag occasioned by the weight of the wringer when it is supported in its operative horizontal position, and means for holding said support member in place in said gear case.

11. In a wringer mechanism, a wringer gear case having upper and lower portions, a wringer supported from the upper portion of said gear case, a support member secured in said gear case and projecting from the lower portion thereof, a hollow wringer column for internally and rotatably receiving the projecting end of said support member and providing a bearing therefor, a member rigid with said wringer column having circumferentially disposed notches, a swing lock lever pivotally carried by said gear case and having a part movable into the stated notches, and means for holding said support member in place in said gear case.

12. A wringer drive for washing machines comprising, a gear case having openings for the reception of a control handle, a driving shaft and a driven shaft, reversing gearing housed in said case and insertable through the stated shaft openings, the opening for said handle being in the form of an elongated cam slot, a cover for said slot held in place by said control handle, and anti-friction means interposed between said control handle and the cam slot of said gear case.

13. In a control device for swinging wringers, the combination with a wringer-drive gearing and a swing-lock, of individual, selectively operable manual control members for said gearing and swing-lock, and interconnecting means associated with said manual control members for moving said swing-lock control member into locking position upon the actuation of said gearing control member.

14. In a control device for swinging wringers, the combination with a wringer-drive gearing and a swing-lock, of individual, selectively operable manual control members for said gearing and swing-lock, said gearing control member having neutral and operative driving positions, and means operated by the manual control member of said gearing for preventing the shifting of said swing-lock control member except when said gearing control member is in its neutral position.

15. In a washing machine, a wringer, a one-

- piece wringer supporting gear case fixed to the wringer and mounted on the machine for pivotal movement about a vertical axis and having openings for the reception of a control handle, a driving shaft and a driven shaft; said gear case being otherwise closed and free from openings, the interior of said gear case having cavities and passageways with non-reentrant sides whereby the gear case may be formed by die-casting the same with non-collapsible cores.
16. In a washing machine, a wringer, a one-piece wringer supporting gear case fixed to the wringer and mounted on the machine for pivotal movement about a vertical axis and having openings for the reception of a driving shaft and a driven shaft; the axis of the shaft openings of said case forming an angle slightly in excess of ninety degrees for the purpose of compensating for the sag of the wringer when occupying its operative positions, vertically disposed support means for said gear case, the interior of said

gear case having cavities and passageways with non-reentrant sides whereby the gear case may be formed by die-casting the same with non-collapsible cores and reversing gearing housed in said case and insertable through the stated shaft 5 openings.

17. In a washing machine, a one-piece gear case having openings for the reception of a control device, a driving shaft and a driven shaft; the interior of said case having passageways and 10 cavities with non-reentrant sides whereby the gear case may be formed by die-casting with non-collapsible cores, reversing gearing housed in said case and insertable through the stated shaft openings, means for mounting said gear case on 15 the machine for movement about a vertical axis, and a wringer secured to said gear case and operatively connected to said driven shaft.
